US00D527056S

(12) **United States Design Patent** (10) **Patent No.:** **US D527,056 S**
Manville (45) **Date of Patent:** **** Aug. 22, 2006**

(54) **CRAFT KIT CONSTRUCTION
COMPONENT—TEAR-DROP FORM WITH
THROUGH-HOLE**

(75) Inventor: **Richard B. Manville**, Los Angeles, CA
(US)

(73) Assignee: **Mattel, Inc.**, El Segundo, CA (US)

(**) Term: **14 Years**

(21) Appl. No.: **29/158,008**

(22) Filed: **Mar. 26, 2002**

(51) LOC (8) Cl. **21-01**

(52) U.S. Cl. **D21/484; D21/386**

(58) **Field of Classification Search** D6/511;
D17/20; D20/22, 23, 27, 28; D21/386, 390,
D21/478–480, 484, 489–492, 504, 505; 84/322;
273/157 R; 446/85, 87, 102, 113; 434/81,
434/82

See application file for complete search history.

(57) **CLAIM**

The ornamental design for a design craft kit construction component—tear-drop form with through-hole, as shown and described.

DESCRIPTION

FIG. 1 is a perspective view of the invention; and,

FIG. 2 is a plan view of the invention.
